ANTENNA FOR TELEVISION AND THE LIKE

Lawrence Kleinberg, Ellenville, and Harry Greenberg,
Kerhonkson, N.Y., assignors, by mesne assignments, to
Avnet, Inc., New York, N.Y., a corporation of New
York

Filed Mar. 29, 1966, Ser. No. 1,675

Term of patent 14 years

(Cl. D26—14)

FIG. 2

FIG. 5

FIGURE 1 is a perspective view of an antenna for television and the like, showing our new design;

FIGURE 2 is a top plan view thereof;

FIGURE 3 is a side elevation thereof, the opposite side being a mirror image of the side shown;

FIGURE 4 is an end elevation as seen from the left of FIG. 1, and

FIGURE 5 is a bottom plan view of the antenna.

The broken line fragmentary showing of a central support rod is for illustrative purposes only.

We claim:

The ornamental design for an antenna for television and the like, substantially as shown and described.
